US0D1026040S

(12) **United States Design Patent** (10) **Patent No.:** **US D1,026,040 S**
(45) **Date of Patent:** **** May 7, 2024**

(54) **WATER PUMP**

(71) Applicant: **Dongguan Booming Electric Industrial Co., Ltd.**, Dongguan (CN)

(72) Inventor: **Sha Yang**, Dongguan (CN)

(73) Assignee: **Dongguan Booming Electric Industrial Co., Ltd.**, Dongguan (CN)

(**) Term: **15 Years**

(21) Appl. No.: **29/919,121**

(22) Filed: **Dec. 1, 2023**

(30) **Foreign Application Priority Data**

Aug. 1, 2023 (CN) 202330486393.1

(51) **LOC (14) Cl.** **15-02**

(57) **CLAIM**

The ornamental design for a water pump, as shown and described.

DESCRIPTION

FIG. 1 is a front, top and right side perspective view of a water pump, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the water pump, which form no part of the claimed design.

1 Claim, 7 Drawing Sheets
